UNITED STATES PATENT OFFICE.

JOHN G. MUELLER, OF DAYTON, OHIO.

RAILWAY-RAIL BRACE.

Application filed May 10, 1926, Serial No. 107,924. Renewed August 22, 1927.

This invention relates to railway rail braces.

In practice it has been found that at curves on tracks where locomotives of different makes, which vary in weight, traction and wheel formation, must run on the same track that it is necessary to constantly repair the track in an effort to avoid accidents and even then the liability of accident is considerable.

10 It is the object of the present invention to provide a rail brace which will effectually brace rails at curves on tracks under these conditions and thereby prevent the rails from spreading and tilting and avoid accidents.

15 A further object of the invention is to provide such a brace which may be easily and quickly applied to the rails; which will be strong and durable; which will be inexpensive; and which may be applied to all standard makes of rails.

In the accompanying drawings:

Fig. 1 is a plan view of my improved brace as applied to a track at a curve.

20 Fig. 2 is an enlarged detail view of one of the members of the brace applied to a rail.

Fig. 3 is a sectional view of a standard track with my brace applied thereto.

25 Fig. 4 is an enlarged sectional view of one of the brace members applied to a rail.

Fig. 5 is an end elevation of the base plate in position on a tie.

30 In Fig. 1 I have shown a curved section of track comprising ties or sleepers 1 and rails 2 and 3, each rail having a base with a web and a tread, the latter being formed with the usual ball 4, being the part on the under surface which is engaged by my improved rail brace.

35 The rail brace comprises a base plate 5 having a bottom surface 6 adapted to rest on a sleeper and two downwardly projecting ears 7 on each side having openings 7a.

40 Barrel-like members 8 join the ears on each side, the openings in the members 8 and forming a continuous opening from the outer face of one ear to the outer face of

45 the other ear to receive the rods 9 for the purpose hereinafter set forth. The upper surface of the base plate has an upwardly

50 projecting portion 10 reinforced by ribs 11 and hollowed out to form a recess or seat 12.

Co-acting with the base plate is a brace member proper having a relatively flat top

55 surface 13 and tapered sides 14. One end

of this brace member is of a width adapted to be positioned in the recess 12 and is rounded, as shown at 15, to provide an adequate bearing surface no matter what the size of the rail is to which the brace is applied.

The opposite end 16 of the brace member is shaped to conform to the contour of the ball of the rail and the upper portion of the web with which it engages. The brace member may be cut away, as shown at 17, for reducing the amount of metal in the casting.

60 The tie rods 9 are threaded on their ends and passed through the openings 7 in base plates positioned on opposite ends of a sleeper beyond the rails. Nuts 18 are applied to the ends of the tie rods and serve to urge the base plates toward the rails so that the brace members proper will be held in firm engagement with the outer sides of the rails of the track, thereby bracing the rails against the tendency of the locomotives to spread them.

65 The usual spikes 1 are employed to secure the rails to the ties. In order to further brace the rails a clamping member 19 may be used to engage the inner side of the rail at the base. This clamping member is provided with an opening 20 to receive the tie rod and the opening is of such size as to 70 provide for adjustment of the clamp to different weight rails. The clamp will be positioned relatively to and held in firm engagement with the base of the rail by nuts 21.

75 When the brace is in bracing position, the brace member proper will extend from the base plate to the ball of the rail, the angle of inclination varying with different sizes of rails, but always sufficient to provide a bracing action to overcome the outward spreading of the rails by the locomotives, especially at sharp curves, where the tendency to spread the rails is very great, and thereby prevent accidents. The clamp 19 will further brace the rail by absorbing the shocks 80 which would otherwise be imposed on the spikes.

85 It will thus be seen that I have provided a rail brace which will effectually prevent the spreading of rails at curves; which will be inexpensive to manufacture; and which will be universal in that it may be applied to rails of different weight without change.

90 It will be understood that I desire to comprehend within my invention such modifica-

tions as may be necessary to adapt it to varying conditions and uses.

Having thus fully described my invention, what I claim as new and desire to secure by Letters Patent, is:—

1. In a railway rail brace, the combination with threaded tie rods, of base plates adapted to be mounted on said tie rods on the outside of the track rails, a brace member proper separate from said base plate and extending between each base plate and adjacent rail, and adjustable means to position said brace members with respect to rails of different sizes and to maintain them at an incline rigidly in engagement with said base plates and rails to prevent the latter from spreading.

2. In a railway rail brace, the combination with threaded tie rods, of a base plate adapted to be mounted on said tie rods adjacent a rail, a brace member proper separate from said base plate and extending between said base plate and rail, and adjustable means on said tie rod for urging said base plate and brace member toward the rail to brace the latter, whereby rail braces of a given size may be adjusted to rails of varying sizes.

3. In a railway rail brace, the combination with tie rods, of base plates having openings to receive said rods and adapted to be positioned on the outside of the track rails, a brace member proper resting on each base plate and engaging with the track rails, and adjustable means for urging said plate and the brace members toward the rails, to brace them, whereby the rail braces of a given size may be adjusted to rails of varying sizes.

4. In a railway rail brace, the combination with threaded tie rods, of base plates each having openings to receive said tie rods and a recess, brace members proper each having one end adapted to rest in the recess in the plate and its opposite end in engagement with a rail, and means for adjusting said base plates so that said brace members proper will be tightly wedged at an incline between the base plates and the rails to brace the latter.

5. In a railway rail brace, the combination with threaded tie rods, of base plates adapted to rest on a tie near the opposite ends thereof and having downwardly extending portions with openings to receive said tie rods, brace members proper separate from the base plate and adapted to be adjusted to rails of different sizes and to extend at an angle from said base plates to the outer sides of the rails of a track, and nuts on said rods for urging said plates toward said rails to maintain the brace members in firm engagement with the plates and rails to brace the latter.

6. In a railway rail brace, the combination with threaded tie rods, of a base plate adapted to be positioned on a tie beyond each

track rail and having openings to receive said tie rods, a brace member proper adapted to be inclined between said base plate and adjacent rail, said base plate having a recess to receive one end of said member, the other end thereof engaging the ball of the rail, and nuts on said tie rods for urging said base plates and brace members toward said rails to prevent the latter from spreading.

7. In a railway rail brace, the combination with threaded tie rods, of base plates adapted to be mounted on said tie rods on the outside of the track rails, clamping members carried by said tie rods between the track rails, means for urging said clamps into engagement with said rails to clamp them, a brace member proper extending between each base plate and adjacent rail, and adjustable means to position said brace members with respect to rails of different sizes and to maintain them at an incline rigidly in engagement with said base plates and rails to prevent the latter from spreading.

8. In a railway rail brace, the combination with threaded tie rods, of a base plate adapted to be mounted on said tie rods adjacent the outside of a rail, clamping members carried by said rods adjacent the inside of a rail, means for urging said clamping members against the base of the rail, a brace member proper extending between said base plate and rail, and adjustable means on said tie rod for urging said base plate and brace member toward the rail, whereby a rail brace of a given size may be adjusted to rails of different sizes.

9. In a railway rail brace, the combination with tie rods, of base plates having openings to receive said rods and adapted to be positioned on the outside of the track rails, clamping members carried by said tie rods between the track rails, adjustable means for urging said clamps into engagement with said rails to clamp them, a brace member proper resting on each base plate and engaging the track rails, and adjustable means for urging said base plates and the brace members toward the rails, to brace them, whereby rail braces of a given size may be adjusted to clamp rails of varying sizes.

10. In a railway rail brace, the combination with threaded tie rods, of base plates adapted to rest on a tie near the opposite ends thereof and having downwardly extending portions with openings to receive said tie rods, brace members proper adapted to be adjusted to rails of different sizes to extend at an angle from said base plates to the outer sides of the rails of a track, clamping members carried by said tie rods and adapted to be adjusted to rails of different sizes to clamp the inner base portions of the track, and nuts on said rods for maintaining the adjusted brace members proper and

clamping members in firm engagement with the rails.

11. In a railway rail brace, the combination with threaded tie rods, of a base plate 5 adapted to be positioned on a tie beyond each track rail and having openings to receive said tie rods, a brace member proper adapted to be inclined between said base plate and adjacent rail, said base plate having a recess to receive one end of said member, the other end thereof engaging the ball 10 of the rail, nuts on said tie rods for urging said base plates and brace members toward

the outer sides of the rails, and clamping members carried by said tie rods for clamp- 15 ing the bases of the rails on the inside.

12. In a railway rail brace, a base plate having a recess and a depending portion at either side with an opening therethrough to receive tie rods, a brace member proper hav- 20 ing one end adapted to be seated in said recess and its opposite end shaped to engage the ball of a rail.

In testimony whereof, I affix my signature.

JOHN G. MUELLER.
